PORT VALVE AND PUMP CONSTRUCTION
FOR INTERNAL COMBUSTION ENGINESHewitt A. Gehres, Mount Vernon, Ohio, assignor
to Cooper-Bessemer Corporation, Mount Ver-
non, Ohio, a corporation of Ohio

Application January 5, 1934, Serial No. 705,317

4 Claims. (Cl. 123—59)

The invention relates to internal combustion engines of the two cycle type, wherein an inlet port is employed in connection with the usual exhaust port, for scavenging and/or supercharging purposes.

The present invention provides an inlet port of the above character which is valve controlled, and with the valve is coordinated a pump member or vane which supplies air under pressure for the port and which may be connected to move with the valve, resulting in a simple, economical and compact construction wherein air under pressure may be supplied for scavenging or supercharging purposes, and wherein the valve and pump may be easily and conjointly driven and timed, thus avoiding the complication and large expense which has been involved in prior constructions for similar purposes. As another possible feature of the invention I disclose a construction of the above character wherein one pump is enabled to supply two cylinders.

Other objects and advantages of the invention will be apparent from the following description taken in connection with the drawings, in which I have shown a preferred form of valve and pump in connection with single acting and double acting engines for the purpose of illustrating the principles of my invention, and in which

Fig. 1 shows a vertical section through a two cylinder two-cycle engine with the invention applied thereto, and showing the position of the parts when one piston is at the bottom limit of its stroke;

Fig. 2 shows a horizontal cross section through the two cylinders taken approximately on the line 2—2 of Fig. 1.

Fig. 3 shows the relative positions of the parts when the piston is on upper dead center;

Fig. 4 shows the relative positions of parts when the same piston is on its down-stroke and just about to uncover the intake port;

Fig. 5 shows the same piston still farther down on its down-stroke, in a position where it has uncovered a part of the exhaust port and more than half opened the intake port, the valve or hub of the oscillating blade pump starting to uncover the lower edge of the intake port;

Fig. 6 shows the same piston at the end of its down-stroke with both the intake and exhaust ports fully uncovered and with the pump blade still traveling to compress air in the lower part of the pump chamber;

Fig. 7 shows the same piston on the upstroke in a position where it has just covered the exhaust port and in which the scavenging port is still

partly open to admit air under pressure into the cylinder;

Fig. 8 shows my invention applied to a double acting engine, with the single piston employed on the lower end of its stroke and full scavenging of the upper end of the cylinder taking place; and

Fig. 9 shows the same arrangement as shown in Fig. 8 with the piston at the upper end of its stroke and the full scavenging of the lower end of the cylinder taking place.

The drawings disclose a preferred type of valve and pump construction, as applied to two-cycle single acting and double acting two cylinder engines of the Diesel type.

In Figs. 1 to 7 I have illustrated my invention as applied to a two-cycle engine with two cylinders. Figs. 1 and 2 show the usual crank case 10, crank shaft 11, piston rod 12 and piston 13 operating in cylinder 14 of the pair of cylinders 14 and 15, Fig.

2. The intake port of the cylinder 14 is shown at 16, Fig. 1, and the exhaust port at 17. It should be understood that the above mentioned port and valve construction with its associated pump, may be used for scavenging and/or super-

charging purposes in conjunction with other means for supplying fuel and air, or may act as the primary supply of air for combustion purposes, and that fuel may be supplied in whole or in part by the pump and injected into the cylinder through the port if desired. References here-

inafter to the above port as an air inlet port are to be understood as comprehending the above possibilities of the invention in its broader aspects.

A valve seat 18 communicating with the outer ends of the ports 16 of the cylinders 14 and 15 is preferably formed in the cylinder casting, and in this is mounted a valve member 19 to which is connected a pump blade 20 which operates in a housing or pump chamber 21, also preferably integral with the cylinder casting. The valve 19 is preferably cylindrical at points adjacent to the ports 16 and recessed at points opposite said ports, as indicated clearly in Figs. 1 and 2. The housing or pump chamber 21 is provided with suitable forms of suction or intake valves 22 and 23.

The housing 21 may be provided with a removable end section 24, as indicated in Fig. 2, to facilitate mounting and dismounting of the valve and pump. The valve 19 is preferably provided with reduced portions bearing in the removable end 24 and in the fixed end of the pump chamber 21, the reduced portion projecting through said latter end being provided with suitable driving means such as a crank arm 25 which may be operated

by a link 26 connected to a crank arm 27 mounted on the crank shaft 11, as indicated in Figs. 1 and 2.

In Fig. 3 I have shown the piston 13 of one of the cylinders, such as the cylinder 14, at the upper end of its stroke and the intake port closed off by the valve 19. As the piston moves down, the pump blade 20 continues its counterclockwise movement and draws air into the lower end of the pump chamber below the blade and then moves clockwise, compressing the air in the lower end of the pump chamber. When the piston in its downward stroke reaches the position shown in Fig. 4 the blade 20 has compressed the air in the lower end of the pump chamber preparatory to scavenging the cylinder, and the valve is still closing the intake port so that no transfer of air can take place. As the piston moves farther in its down-stroke it opens communication between the inlet port and the cylinder space and also opens the exhaust port 17 so that when the exhaust port is partly open, as shown in Fig. 5, the intake port is preferably more than half open and the valve 18 of the pump begins to uncover the lower edge of the intake port, thereby starting the scavenging action. Further movement of the piston in its down-stroke into the position shown in Fig. 6 causes both the intake and exhaust ports to open, and as the valve 18 uncovers the intake port the scavenging action proceeds. Fig. 6 shows the piston at the end of its down-stroke with the intake and exhaust ports wide open and valve 18 open, full scavenging taking effect and continuing until the parts assume the position shown in Fig. 7.

Fig. 7 shows the piston on the up-stroke at a point where it has just covered the exhaust port. The intake port may be still open and the scavenging blade, which has moved from the position shown in Fig. 6 to the position shown in Fig. 7, is just completing its full travel and is charging the last remaining part of the air into the cylinder of the engine in the form of a super-charge. The use of valve 18 for controlling port 16 instead of relying on piston 13 for this purpose, may keep the auxiliary port 16 open after the exhaust port 17 has closed (as indicated in Fig. 7) whereby a supercharging effect may be obtained if desired.

The same cycle of events takes place in the adjacent cylinder 15, except that it is scavenged and supercharged by air compressed in the upper end of the pump housing by the upper side of the blade, the upper side of the valve 18 being cut away, as shown in Fig. 2, to control the intake port of this cylinder. With this arrangement for single acting engines, one of these double acting scavenging pumps will furnish the supply of air for two adjacent cylinders for scavenging and supercharging purposes. In a multiple cylinder engine, each pair of cylinders would preferably have one double acting pump, each side of which scavenges and supercharges the adjacent cylinder.

The illustrative embodiment of my invention that I have described in connection with the single acting engine can be applied with slight variation to a double acting engine, in which case there is one pump for each double acting cylinder. I have shown such a construction in Figs. 8 and 9.

Fig. 8 shows the piston 30 at the lower end of its stroke in the double-ended cylinder 31, full scavenging of the upper end 32 of the cylinder

taking place from the upper side of the pump blade 33.

In Fig. 9 I have shown the piston 30 at the upper end of its stroke so that the lower side of the scavenging pump is scavenging the lower end 34 of the double-ended cylinder 31. The double-ended cylinder is provided with a single exhaust port 35 and a single intake port 36 which communicates with a cylindrical opening receiving the valve 37 which carries the pump blade 33. The valve is cut away on both sides of the blade in alignment with the port 36, as indicated clearly on Figs. 8 and 9. The pump casing 38 and the suction valves 39 and 40 may be of any suitable construction, as indicated diagrammatically.

It will be noted from Figs. 8 and 9 that the upper and lower ends of the intake port 36 are so arranged with respect to the upper and lower ends of the exhaust port 35, that scavenging air may be admitted through the intake port before the exhaust port is open and that supercharging air may be admitted through the intake port after the exhaust port has been closed. The solid portion of the valve 37 functions to close communication between the upper and lower sides of the pump chamber with the port so that air drawn into the lower end, as shown in Fig. 8, will be confined therein and will be later compressed as the blade moves downwardly to compress and force the air into the lower end 34 of the cylinder 31. The pump shown in Figs. 8 and 9 operates in all respects the same as the pump shown in Figs. 1 to 7.

It will now be apparent that I have provided a simple, compact, economical and efficient device for scavenging and supercharging cylinders of internal combustion engines. It is to be understood, however, that the specific mechanism illustrated and described constitutes but one embodiment of the principles of my invention, and that words of description imported from the specification into the claims are to be considered as such and not words of limitation, as it is my intention to cover all devices which fall within the principles of my invention, as defined in the appended claims.

I claim:

1. An internal combustion engine of the two cycle type having cylinders each provided with an exhaust port and an inlet port located near one limit of the piston stroke, a common pump chamber located adjacent said inlet ports, valve members respectively controlling communication between different parts of said pump chamber and said inlet ports, a pump member which is connected to said valve members and which divides the pump chamber into different parts respectively communicating with said valve members, and a common means for driving said valves and pump members in unison, whereby said pump member operates during a given phase of its movement to draw in air for one inlet port into one part of said pump chamber when its valve is closed and supply air under pressure from another part of said pump chamber to the other inlet port when its respective valve is open.

2. An internal combustion engine of the two cycle type having aligned cylinders and a piston member reciprocating therein, inlet port means for each of said cylinders located intermediate the same, a common pump chamber located adjacent said inlet port means, a valve member interposed between said pump chamber and inlet port means, adapted selectively to open and close communication between different parts of said

5 pump chamber and portions of the inlet port means leading respectively to said cylinders, a pump member within said chamber dividing said chamber into different parts and connected to said valve member to move therewith, and common means for driving said pump-member and valve members in unison, whereby said pump and valve members operate during a given phase of movement to draw in air for one cylinder into one of 10 said parts of the pump chamber when the valve member closes communication to the corresponding cylinder and to supply air under pressure for the other cylinder from another part of the pump chamber when said valve member opens communication between said last mentioned cylinder 15 and part of the pump chamber.

3. An internal combustion engine of the two cycle type, having adjacent cylinders provided with inlet port means located near one limit of 20 the piston stroke, an angularly movable valve member located adjacent said inlet port means and controlling communication therethrough to each of said cylinders, a pump chamber located adjacent said valve member, a pump blade carried by said valve member and dividing said pump chamber into 25 parts respectively serving said cylinders, means for admitting air to each of said parts of the chamber, and means for moving said valve member angularly divided by said valve member and dividing said chamber into two parts, means for admitting air to each of said parts of the pump chamber, and means for moving said valve member angularly

through successive phases in which it alternately opens and closes communication between said parts of the pump chamber and the respective cylinders while the pump blade acts alternately to draw air into the respective parts of the pump 5 chamber and supply air under pressure therefrom to the respective cylinders.

4. An internal combustion engine of the two cycle type, having cylinders disposed side by side and inlet ports both located near one limit of 10 the piston stroke, a common angularly movable valve member extending between said inlet ports and controlling communication to both of them, a pump chamber located adjacent said valve member, a pump blade carried by said valve 15 member and dividing said pump chamber into parts respectively serving said cylinders, means for admitting air to each of said parts of the chamber, and means for moving said valve member angularly through successive phases in which 20 it alternately opens and closes communication between said parts of the pump chamber and the respective cylinders while the pump blade acts alternately to draw air into the respective parts of the pump chamber and supply air under 25 pressure therefrom to the respective cylinders.
